CLAIM

The ornamental design for a paint mixing paddle, as shown and described.

DESCRIPTION

FIG. 1 is a side elevational view for a paint mixing paddle, showing our new design, the opposite side being the mirror image thereof;

FIG. 2 is a rear elevational view thereof;

FIG. 3 is a front elevational view thereof;

FIG. 4 is a top plan view thereof; and

FIG. 5 is a bottom plan view thereof.

FIG. 2

FIG. 1

FIG. 3

FIG. 4

FIG. 5
